UNITED STATES PATENT OFFICE.

JOHN VINCENT BOX, OF LOS ANGELES, CALIFORNIA, ASSIGNOR OF ONE-THIRD TO
C. R. LITTLE AND ONE-THIRD TO (MRS.) WILLIAM PAYNE MARTIN, (WIDOW,) BOTH OF WHITTIER, CALIFORNIA.

ROTARY WELL-DRILLING HEAD.

1,383,785.

Specification of Letters Patent.

Patented July 5, 1921.

Application filed September 22, 1919. Serial No. 325,552.

To all whom it may concern:

Be it known that I, JOHN VINCENT Box, a citizen of the United States, residing at Los Angeles, in the county of Los Angeles 5 and State of California, have invented new and useful Improvements in Rotary Well-Drilling Heads, of which the following is a specification.

This invention relates to hydraulic heads 10 employed in the operation of sinking oil wells and water wells by means of a rotary drill operating in connection with water under pressure.

In drills of this kind the drill-boring bit 15 is hollow and is connected by a hollow shaft with rotary power at the top of the ground. Water under pressure is introduced through a hose and suitable connections into the top of the hollow shaft and said connections and 20 shaft are handled by a cable attached to a practically non-rotating head, with relation to which the hollow shaft is rotated. The weight of the bit and shaft is supported by said head which in turn is carried by the 25 cable and is raised and lowered thereby as the character of the drilling and attendant operations require. Said shaft is connected with the power apparatus through the medium of an angular section which is adapted 30 to slide up and down relative to the power applying means by which it is rotated.

An object of the invention is to provide a practical antifriction support for said shaft and bit.

It has recently been found practicable and desirable to drill oil wells to greater depths 35 than has heretofore been common, and wells are now being sunk to depths of five thousand feet and more as well as less. It is 40 common in this work to employ a long tubular rotary drilling shaft the weight of which in some cases is more than seventy-five tons, and such shafts are revolved at a speed of from about fifty to one hundred 45 revolutions per minute, more or less, and the tool is lowered to deepen the cut while revolving at such speed. The power for thus making the cut is transmitted through said long heavy tubular shafts which are 50 usually from four to six inches in diameter and are necessarily more or less flexible on account of the great length. Owing to the flexibility of the shaft, the rotation thereof produces a swaying, waving and wobbling

which causes such action upon the anti-friction bearings of the hydraulic head by 55 which the shaft is supported, as to rapidly put the same out of commission.

This has been a source of great loss of 60 money, time and material. An object of this invention is to avoid such loss.

In hydraulic heads of this character one of the chief difficulties encountered in the drilling of deep wells has arisen from the failure of the anti-friction bearing to stand 65 and hold up under the heavy strain and thrust caused by the operating forces. An object of this invention is to make provision 70 whereby such strain and thrust will be compensated for and reduced to a minimum.

I have discovered that the destruction of the anti-friction bearing is caused by outward thrust of the rollers in such bearings and that such outward thrust can be avoided by a proper construction and arrangement 75 of the parts going to make up the bearing.

An object of this invention is to provide such an anti-friction support for the heavy weight of the rotary shaft and boring bit, 80 as to effectively avoid jamming, excessive wear, displacement or destruction of the parts of such a support under the conditions above detailed, and to maintain the shaft in true axial alinement during its rotation.

The best anti-friction roller bearings for this purpose heretofore known to me are constructed with truncated conical rollers arranged with their axes in a horizontal plane; said rollers resting upon an annular 90 support or raceway having the form of a truncated cone, the produced apex of which cone is centrally located above the level of the orifice in the roller support through which the shaft extends.

I have determined that with such construction the gravitational pressure and the centrifugal force to which the rollers are subjected tend to move the rollers outward endwise, and that the end thrust of the rollers thus produced against the means to retain the rollers in operative position, results in great friction, jamming, and wear which causes looseness between the rollers and necessitates frequent replacement of the 105 roller-bearing parts and also replacement of journal bearings for the shaft.

I have discovered that the remedy for

these difficulties and destructive action, is to incline downwardly and inwardly the annular floor which supports the rollers, so that the supporting raceway floor is provided with a cavity which is the form of an inverted truncated cone, the produced apex of which is central to and below the level of the rim of the orifice through which the shaft extends downwardly. On this raceway I mount uniform truncated conical rollers; that is to say, rollers which are alike and are frustums of cones, of such pitch that when the rollers are in place on said floor, the produced apexes of the rollers will terminate at the produced apex of said cavity.

In this respect my invention is broadly new, basic and pioneer and is at present practically indispensable in the boring of said wells of approximately 5000 feet depth by rotary drills.

I also so construct the outer ends of the rollers that the outward thrust, if any, is borne with minimum friction and wear.

A principle of the invention is that the damaging end-thrust of the tapering rollers is eliminated by so constructing the raceway and the truncated conical rollers and so inclining the rollers that their axes converge downwardly as traces of an inverted cone, said rollers being supported on an annular concave floor, the upper surface of which is parallel to such inverted cone. As a consequence of this construction and arrangement the resolution of forces applied to the frusto-conical rollers practically maintains them *in situ*. In practical construction I make the outer end of each conical roller as the segment of a sphere, thus affording a surface annularly inclined outward toward the axis of each roller. The outer rim walls of the upper and lower bearing plates of the raceway are concaved to conform to the semispherical roller ends. As a result of this construction the destructive action above referred to is practically done away with and the operation is made smooth and comparatively frictionless.

An object of the invention is to provide a superior anti-thrust bearing applicable to purposes above indicated, and a broadly new pioneer and basic feature in this respect is a thrust bearing comprising an annular base plate having an inverted truncated conical cavity, the apex of the cone being at the produced axis of the orifice of the base; and tapering rollers on the floor of said cavity; the axes of said rollers converging to said produced apex of the floor of the inverted truncated conical cavity, and means whereby the shaft, the supporting cable and the hose are practically connected for the various purposes to which they are adapted.

The antifriction bearing is contained within 65 in a suitable housing cup inside of which a

hollow journal section of the shaft is mounted. The sections of the shaft are connected together by couplings, and the shaft and connected parts may be supported by any suitable means applied under a coupling or beneath the cup; and an object of this invention is to so construct the connection between the cable support and the cup or lower portion of the housing of the anti-friction bearing; as to allow a convenient removal of an upper part, cap or cover from the cup of such housing; and this is accomplished by connecting a bail to such cap or cover and detachably connecting the cap or cover with the lower portion or cup of the housing; said cap and cup being connected to the shaft in such a way as to prevent escape of lubricant, and said cap being adapted to allow lubricant to be introduced into the housing for the purpose of lubricating the bearings.

A feature of my invention is the provision of a flange upon said journal section for the purpose of frictionally engaging a bearing plate revoluble upon said tapering rollers, 90 arrangement of antifriction means on the flange as to minimize friction between the flange and the cap of said housing and to steady the shaft during its rotative movement.

Other objects, advantages and features of the invention may appear from the accompanying drawings, the subjoined detailed description and the appended claims.

The accompanying drawings illustrate the invention.

Figure 1 is a fragmental elevation of a hydraulic head constructed in accordance with this invention and in operative position.

Fig. 2 is a plan of the antifriction members 105 of the bearing with the separating guide frame or spider in position on the base plate of the bearing.

Fig. 3 is an axial section on line 2° Fig. 2.

Fig. 4 is an axial section of the power table.

Fig. 5 is an enlarged elevation of the hydraulic head.

Fig. 6 is an axial section of the hydraulic head on line 6°, Fig. 5.

1, is the sliding power section of the rotating shaft, which supports the drill bit, not shown, that operates at the bottom of the well and that is driven by the bevel gears 2, 3, and runs through the horizontal bevel gear 3, and down through the casing 4 through 120 which the water and the borings are discharged to the surface in a well known manner. Said power shaft section 1 is connected by a coupling 1'' to the tubular drilling shank 5, to which the bit, not shown, is 125 fixed.

It is customary to suspend the shaft elements just described from a supporting head at the top of the sliding shaft by antifriction means, but the weight of the suspended tools 130

for use in deep well boring is so great that the antifriction devices heretofore employed have been subject to destruction in various ways.

- 5 In the drawings a tubular journal section 6 of the shaft provided with a supporting means in the form of a flange 7 is shown supported by a rotatable annular plate 8 having a truncated conical raceway 9 and resting on 10 truncated conical rollers 10, that are spaced apart by space bars 11 and rest on a truncated conical raceway 12.

The raceway 12 is a truncated conical depression in an annular base plate 13; and the 15 produced apex of said depression is coincident with the axis a of the tubular journal section 6 of the drill shaft. The truncated cone rollers 10 taper at such an angle that their produced axes converge to the produced 20 apex of the lower raceway 12. The raceway 9 is the frustum of an inverted cone, the produced apex of which cone is also coincident with the apex of the inverted cavity forming the raceway 12.

25 The spacing bars 11 are connected together at their outer ends by the outer ring 14 and are connected together at their inner ends by the inner ring 14'. Said inner ring has an annular foot 15 that rests upon the inner 30 margin of the lower raceway 12.

Said lower raceway is formed in an annular plate 13 which is provided at its periphery with an upwardly projecting rim 17. The upper annular plate 8 is also provided 35 with a rim 18 and these two rims are spaced apart to accommodate the outer ring 13 without frictional contact therewith.

Said lower plate 13 is contained within a housing formed by the cup 19 journaled to 40 the shaft journal section 6 and provided with the gland 20 fitting said shaft 6. Said cup has a cavity, the floor of which is in the form of the frustum of an inverted cone, and upon said cup of the housing is the housing cap 21 detachably fixed to the housing cup by bolts 22.

The flange 7 is provided with a ball raceway 23 in which anti-friction balls 24 are arranged to run; the same being borne upon 50 by the cone 25 which is externally screw-threaded and is screwed down through the annular cap 21 and is there secured by the threaded lock ring 26. The cone 25 is the lower terminal of a cylindrical gland in 5 which is placed packing 27 secured by the bushing 28. The cone portion of the gland is journaled upon the shaft 6; the antifriction means 23, 24 and 25 co-operate for minimizing friction between the flange 7 and the cap 21 and for steadyng the shaft 6 during its rotative movement; and the gland packing 27 and bushing 28 close the joint so that said shaft 6 will not have any lateral vibratory movement relative to the cap 21, and leakage 65 of lubricant is avoided.

The cap 21 is provided with trunnions 29 to which the bail 30 is journaled for the purpose of suspending the cap. Said trunnions 29 are lateral co-axial cylindrical projections from the upright arms 31 of the frame 70 which is bridged over the top by the cross head 32 through the center of which is provided an orifice 33 through which the packing head 34 of the goose-neck 35 extends. Said packing head is provided with the lateral flange 36 that rests upon the cross-head 32, and is secured thereto by bolts 37. Said packing head 34 is adapted by the threaded end 38 of the goose neck 35 to be connected with the valved hose coupling 39.

75 The top of the bearing plate 8 is provided with a truncated conical cavity and the flange 7 is an inverted truncated cone fitting therein.

In practice when the parts are in position 85 as shown in Fig. 6 and are suspended by the line 40 in the usual manner, the force of gravity tends to hold the journal section 6 of the shaft in vertical position.

The bearing plate 8 does not contact with 90 the cup 19 or the cap 21 and the base plate 13 does not contact with the journal section 6; consequently, the bearing plate 8 revolves freely upon the truncated conical rollers 10, and friction between the flange 7, (which by 95 its engagement with the bearing plate causes the latter to revolve the shaft 6,) and the cap, is minimized by the antifriction means 23, 24 and 25, and the glands 20 at the bottom of the cup and the gland and packing at 100 the top of the cap prevent escape from the housing of lubricant which may be introduced in any desired and well known way.

A nipple 41, having a flange 42 is fixed to the top of the journal section 6, of the shaft, 105 by cap screws 43 and extends from said flange 42 down into the journal section 6 and up into the packing head 34 of the goose neck. The connection between said packing head and nipple is made water tight by the 110 packing 44, held in place by the gland 45 and jam nut 46.

When it is desired to gain access to the antifriction bearing inside the housing 19, 21, the shaft may be lowered to allow a coupling such as the coupling 47 to rest upon 115 a suitable support such as the hub 48, of the driving gear 3 and then the cup 19 may be supported and the bolts 22 removed; thus releasing the cap 21; whereupon the line 40 120 may be operated to raise the cap from the cup, thus giving access to the cup.

By lowering the cup, the bearing plate 8 is lowered from the flange 7, whereupon the flange 7 may be grappled by hooks inserted 125 into seats 50 thus giving access to the rollers 10 and to the retainer or separating spider without disassembling the parts.

The outer ends of the rollers are of semi-spherical form as indicated at 51 and the 130

- inverted cone cavities which accommodate the rollers 10 terminate at their outer rims in annular stops 52, 53 that are conformed to the semispherical butts 51 of the rollers.
5. The result of this construction is that the lines of force as applied to the rollers by the weight of the tool and hollow shaft are revolved in practically a direct downward thrust upon said rollers and the tendency to 10 squeeze the rollers outward endwise is overcome by the contact with the semispherical butts of the outer ends of the rollers and the concave rims 52 that intercept the same.
- I claim:
15. 1. In a hydraulic head, the combination with a hollow shaft journal provided with a flange, of a bearing plate for said flange; said bearing plate being provided with an inverted truncated conical raceway; a base 20 plate provided with a truncated conical inwardly depressed raceway; and truncated rollers in said raceways.
2. In a hydraulic head, the combination with a hollow shaft journal provided with a 25 flange, of a bearing plate for said flange; said bearing plate being provided with an inverted truncated conical raceway; a base plate provided with a truncated conical inwardly depressed raceway; and truncated 30 conical rollers in said raceways; the apexes of the produced cones of the truncated raceways and rollers converging to the axis of said shaft.
3. In a hydraulic head, the combination 35 with a hollow shaft journal section provided with a flange, of a bearing plate for said flange; said bearing plate being provided with an inverted truncated conical raceway; a base plate provided with a truncated conical 40 inwardly depressed raceway; and truncated conical rollers in said raceways, the apexes of the produced cones of the truncated raceways and rollers converging to a common point in the axis of the hollow shaft journal section.
45. 4. The combination with a bearing cup, of a base plate seated in said cup and provided in its upper face with a truncated conical inward depression; truncated conical rollers in said depression, a bearing plate provided 50 with a truncated conical raceway on the under side and mounted on said rollers; a hollow shaft journalized in said cup and provided with a flange resting on said bearing plate; an annular cap detachably secured to 55 said bearing cup; means connected to the cap to raise and lower the same, and a connection for introducing water under pressure to the hollow shaft.
5. The combination with a cup, of a shaft 60 journalized therein and provided with a flange; a base plate provided with a raceway on its upper face; a spacing spider provided with a foot supported by said raceway; roller bearings in said raceway; a bearing plate on said roller bearings and sup- 65 porting the flange of said journal section; a cap detachably connected to the cup; and means connected to the cap to raise and lower the same.
6. In a hydraulic head, the combination 70 with an antifriction bearing, of a housing for said bearing, said housing comprising a cup and a cap; a journal section of a shaft provided on its upper face with a raceway; antifriction means in the raceway, and a cone 75 screwed through the cap to cooperate with said antifriction means in said raceway; and packing between the shaft and the cone.
7. In a hydraulic head, the combination 80 with a hollow shaft journal provided with supporting means, of a bearing plate for said supporting means; said bearing plate being provided with an inverted truncated conical raceway, a base plate provided with a truncated conical inwardly depressed raceway and truncated rollers in said raceways. 85
8. In a hydraulic head, the combination with a hollow shaft journal provided with a flange, of a bearing plate for said flange; said bearing plate being provided with an inverted truncated conical raceway; a base 90 plate provided with a truncated conical inwardly depressed raceway; a housing inclosing said bearing plate and said base plate, said housing comprising a cup having a cap detachably secured thereon; antifriction means on said flange for minimizing friction between the flange and the cap and for 95 steadyng the shaft during its rotative movement; and truncated rollers in said 100 raceways.
9. In a hydraulic head, the combination with a hollow shaft journal provided with a flange, of a bearing plate for said flange; said bearing plate being provided with an inverted truncated conical raceway; a base 105 plate provided with a truncated conical inwardly depressed raceway; a housing inclosing said bearing plate and said base plate, said housing comprising a cup having a cap detachably secured thereon; antifriction means on said flange for minimizing friction between the flange and the cap and for 110 steadyng the shaft during its rotative movement; and truncated conical rollers in 115 said raceways; the apexes of the produced cones of the truncated raceways and rollers converging to the axis of said shaft.
10. In a hydraulic head, the combination with a hollow shaft journal section provided 120 with a flange, of a bearing plate for said flange; said bearing plate being provided with an inverted truncated conical raceway; a base plate provided with a truncated conical 125 depressed raceway; a housing inclosing said bearing plate and said base plate, said housing comprising a cup having a cap detachably secured thereon; antifriction means on said flange for minimizing friction between the flange and the cap and for 130

- steadyng the shaft during its rotative movement; and truncated conical rollers in said raceways, the apexes of the produced cones of the truncated raceways and rollers 5 converging to a common point in the axis of the hollow shaft journal section.
11. The combination with a bearing cup, of a base plate seated in said cup and provided in its upper face with a truncated conical depression; truncated conical rollers in said depression, a bearing plate provided with a truncated conical raceway on the under side and mounted on said rollers; a hollow shaft journaled in said cup and provided with a flange resting on said bearing plate; an annular cap detachably secured to said bearing cup; antifriction means on said flange for minimizing friction between the flange and the cap and for steadyng the shaft during its rotative movement; means connected to the cap to raise and lower the same, and a connection for introducing water under pressure to the hollow shaft.
12. The combination with a cup, of a shaft journaled therein and provided with a flange; a base plate provided with a raceway on its upper face; a spacing spider provided with a foot supported by said race-
- way; roller bearings in said raceway; a bearing plate on said roller bearings and supporting the flange of said journal section; a cap detachably connected to the cup; antifriction means on said flange for minimizing friction between the flange and the cap and for steadyng the shaft during its rotative movement; and means connected to the cap to raise and lower the same.
13. In a hydraulic head, the combination with an antifriction bearing, of a housing for said bearing, said housing comprising a cup and a cap; a journal section of a shaft mounted in the antifriction bearing and provided on its upper face with a raceway; antifriction means in the raceway, and a cone screwed through the cap to coöperate with said antifriction means in said raceway for minimizing friction between the cap and the journal section and for steadyng the shaft during its rotative movement; and packing between the shaft and the cone.

In testimony whereof, I have hereunto set my hand at Los Angeles, California, this 11th day of September, 1919.

JOHN VINCENT BOX.

Witness:

JAMES R. TOWNSEND.
